(57) CLAIM

The ornamental design for a controller housing for a well management system, as shown and described.

DESCRIPTION

FIG. 1 is a top front right perspective view of an embodiment of a controller housing for a well management system showing a new design;

FIG. 2 is a top front left perspective view of the controller housing for a well management system illustrated in FIG. 1; FIG. 3 is a bottom front right perspective view of the controller housing for a well management system illustrated in FIG. 1;

FIG. 4 is a bottom front left perspective view of the controller housing for a well management system illustrated in FIG. 1;

FIG. 5 is a front view of the controller housing for a well management system illustrated in FIG. 1;

FIG. 6 is a rear view of the controller housing for a well management system illustrated in FIG. 1;

FIG. 7 is a right side view of the controller housing for a well management system illustrated in FIG. 1;

FIG. 8 is a left side view of the controller housing for a well management system illustrated in FIG. 1;

FIG. 9 is a top view of the controller housing for a well management system illustrated in FIGS. 1; and,

FIG. 10 is a bottom view of the controller housing for a well management system illustrated in FIG. 1.

The broken lines show portions of the design that form no part of the claimed design.
